DROP PIT APPARATUS

Hugh K. Christie, Harvey, Ill., assignor to Whiting Corporation, Harvey, Ill., a corporation of Illinois

Application August 17, 1939, Serial No. 290,598

11 Claims.

(Cl. 104—32)

The invention relates to drop pit apparatus for handling wheels and trucks of railway equipment.

One object of the invention is to provide a compound table which comprises a central section adapted to bridge the pit and end-sections which are co-terminous with the side-beams of the main section and can be lifted and lowered separately and independently of the central section, and means for selectively dropping either a single pair of wheels at either end of, or an entire truck.

Another object of the invention is to provide a compound table which comprises a plurality of sections adapted to bridge the pit with wheels on one of the sections which are adapted to roll on rails on the lifting mechanism which extend completely across the pit so that it may be wheeled directly from the lifting mechanism onto floor tracks at either side of the pit.

Another object of the invention is to provide a compound table comprising a central section and a plurality of separately lowerable end-sections, which are provided with laterally off-set wheels for selective engagement by rails on the lifting carriage.

Another object of the invention is to provide a compound drop table in which one of the separably lowerable sections is provided with means for manually propelling a wheeled table section on and off rails on the lifting mechanism.

Other objects of the invention will appear from the description of the details.

The invention consists in the several novel features which are hereinafter set forth and are more particularly defined by claims at the conclusion hereof.

In the drawings: Fig. 1 is a plan of the compound table exemplifying the invention, the flooring being omitted. Fig. 2 is a section taken on line 2—2 of Fig. 1, the lifting carriage being shown below the table. Fig. 3 is a perspective of the central table-section which is provided with side-beams adapted to span the pit. Fig. 4 is a perspective of the lifting-carriage. Fig. 5 is a perspective of one of the end-sections of the drop-table. Fig. 5^a is a transverse section through one of the end-sections of the drop-table illustrating the propelling mechanism in its operative position. Fig. 6 is a section on line 6—6 of Fig. 1, illustrating the lifting carriage engaging one of the end-sections of the table to raise or lower that section independently of

the others. Fig. 7 is a section on line 7—7 of Fig. 1, illustrating the lifting-carriage in position for simultaneously engaging and conjointly raising or lowering all of the sections. Fig. 8 is a section illustrating the lifting-carriage raised to floor level and one of the end-sections being rolled off onto one of the floor-tracks.

The invention is exemplified with a shop installation which usually comprises a series of tracks consisting of pairs of rails *b* arranged in any suitable manner on the shop floor and terminating at the sides of a pit *a* which intersects the floor-tracks, a drop-table adapted to be raised and lowered in the pit and comprising a central section *c* and end-sections *d*, *d*¹ and a carriage *f* for raising or lowering the table. The central table-section *c* comprises a pair of longitudinal I-beams *10* at its sides which extend entirely across the pit and cross I-beams *12* which rigidly connect beams *10* at points spaced some distance inwardly of the ends of the beams *10*. Beams *10* extend entirely across the pit to releasably support central section *c* directly from the pit-walls. Beams *12* are spaced from one side of the pit to leave an open-ended space at each end of the table between beams *10*, beams *12* which, with the side-walls of the pit, respectively, form substantially rectangular spaces for the end-sections *d*, *d*¹. Longitudinal I-beams *c*¹ are secured to, and extend between, cross-beams *12* of table-section *c* to support rail-sections *c*² which terminate at the outer sides of beams *12* and extend across said table-section. Table-section *c* is releasably supported from the pit-walls by four bolts *13* which are slidably mounted in fixed guides *14* adjacent the outer ends of beams *10*, respectively. The outer ends of bolts *13* are adapted to engage the lower flanges of I-beams *m* which are built into the pit-walls, to support section *c*. A hand-lever *15* at one side of table-section *c* is fixed to a transverse shaft *16* which is journaled in beams *10* and has double-armed levers *17* for operating links *18* to simultaneously shift all of the locking-bolts *13*. When lever *15* is swung into its lowered position, the projecting ends of bolts *13* will rest on beams *m* and support the beams *10* on table-sections *c* in track-bridging position from the pit-walls. When lever *15* is swung upwardly, bolts *13* will be withdrawn from engagement with beams *m* and the table-section *c* will be released so that it can be raised or lowered by the lifting carriage *f*. Each table-section *d*, *d*¹ is rectangular and fits in one of

the open-ended spaces in section *c*. The outer end of each of the sections *d*, *d*¹ extends to one of the side-walls of the pit to form table-sections. One pair of wheels of a truck can be spotted on each or either of the sections *d*, *d*¹ so that either pair of wheels can be dropped independently of the other wheels on a locomotive or truck. The outer end of each table-section *d*, *d*¹ is substantially conterminous with the adjacent ends of beam 10 of table-section *c*. 10 Each table-section *d*, *d*¹ is built up of channelled side-beams 19, a cross I-beam 20 at its outer end, and a cross I-beam 21 at its inner end, which are secured together to form a rigid rectangular frame or structure. Longitudinal 15 I-beams 22 are fixed to, and extend between, cross-beams 20, 21 to support rail-sections *d*² which extend from end to end of the table-sections *d*, *d*¹, respectively. Bolts 25 are slidably mounted in guides 26 which are fixed to beams 20 22 adjacent the outer ends of each of the sections *d*, *d*¹ and are adapted to project, respectively, to engage the beams *m* in the pit-walls and support the outer ends of table-sections *d*, *d*¹ from the pit. Bolts 27 are slidably mounted in guides fixed to, and adjacent, the inner end of beams 22 of each table-section *d*, *d*¹ and are adapted to be projected to support the inner ends of said sections from cross-beams 12 of table-section *c*. A hand-lever 28 is provided for simultaneously shifting the bolts 25, 27 for each section *d*, *d*¹ and is fixed to a shaft 29 which is journaled in beams 19 and has affixed thereto levers 30 which are connected by links 31 to bolts 25 and 27. When one of the levers 28 is swung downwardly, bolts 25 will be projected to engage one of the beams *m* in the adjacent walls and bolts 27 will be projected to engage cross-beam 12 of table-section *c*, so that the table-section *d* or *d*¹ will be supported by, and between, the pit-wall and the table-section *c*.

When sections *d*, *d*¹ are unlocked from the pit, and beams 12 of table section *c*, either of said sections may be raised or lowered independently of section *c*, or of each other.

The lifting mechanism comprises a vertically movable carriage which is built up of longitudinal I-beams 34 and a pair of cross channel beams 35 at each end of the carriage, all rigidly secured together. A saddle 38 is fixedly secured at each corner of the carriage between the pairs of cross-beams 35 which are spaced apart. The mechanism for raising and lowering carriage *f* comprises a series of four vertical screws 40 which are threaded to nuts 41 upon which the saddles 38 of carriage *f* are supported. These screws are mounted upon a trolley *g* which is provided with wheels *g*¹ adapted to travel on rails which extend longitudinally of, and are laid on the bottom of, the pit. The upper ends of the screws 40 are journaled in bearings 40^a in the upper end of the channelled guide-columns *f*² which are fixedly secured on the trolley. The outer ends of cross-beams 35 extend in the channels of columns *f*² to guide the carriage vertically. The four screws 40 are synchronously driven by a motor and suitable gearing mounted on the trolley, as well understood in the art. The simultaneous rotation of screws 40 rectilinearly raises or lowers the lifting carriage *f*.

In practice, it is necessary to engage the lifting mechanism with all of the table-sections conjointly for dropping a truck or to engage either one or the other of the end-sections *d*, *d*¹ for dropping a single pair of wheels from a truck on the

table. It is also necessary to raise all of the table-sections conjointly above track level for uncoupling a truck from the rolling stock and to raise either of the table-sections *d*, *d*¹ above track level to uncouple the pair of wheels thereon from the truck. It is also desirable when a pair of wheels has been dropped, transferred and raised to an unoccupied floor track, to expeditiously transfer the wheel from the lifting-carriage to the floor tracks at either side of the pit.

Rails 34^a are fixed to the upper faces of the longitudinal beams 34 of the lifting-carriage *f*. Beams 34 and rails 34^a thereon extend across the pit and are spaced apart transversely conformably to the spacing between the longitudinal beams 22 of end-sections *d*, *d*¹ and the longitudinal beams *c*¹ of the section *c*, so that rails 34^a may be brought into vertical alignment with said longitudinal beams of all the sections.

When the lifting-carriage is centered under, and transversely of, the drop-table, and the carriage is raised, rails 34 will engage the under side of longitudinal beams *c*¹ and cross-beams 12 of table-section *c* and longitudinal beams 22 of table-sections *d*, *d*¹ to transmit the load on the rail-sections directly through the table to the lifting-carriage, as shown in Fig. 7. When the carriage is thus positioned, all of the table-sections will be supported on the lifting-carriage for conjoint raising or lowering of all of said sections with the load thereon. The cross-beams 35 of the lifting-carriage are extended laterally and provided with abutments 37 for engaging the outer ends of the longitudinal beams 10 of the central table-section *c*, when the carriage is centered under the table. Abutments 37 are provided with inclined upturned flanges for positioning the beams 10 on the lifting-carriage and preventing relative lateral movement between them when abutments 37 are engaged with beams 10. This construction results in efficiently supporting the table on the carriage *f* when the table is heavily loaded and insures rectilinear vertical movement of all of the table-sections by said carriage.

Each of the table-sections *d*, *d*¹ is provided on its under side with a set of four wheels 48 which are spaced apart transversely conformably to the spacing between the rails 34^a on the lifting-carriage and are adapted to be engaged thereby. 50 The wheels of either of the table-sections *d*, *d*¹, when they are supported on the tracks 34^a, permit said sections to be run over the lifting-carriage and from one side of the pit to the other. The rails 34^a extend between the sides of the pit and are adapted to completely bridge the space between sections of the rails of tracks *f* on opposite sides of the pit when the lifting-carriage is raised to bring rails 34^a to floor level and aligned with the rail-sections of tracks *b*. This makes it possible to roll either of the table-sections *d*, *d*¹ from rails 34^a to the tracks at either side of the pit.

The wheels at each side of sections *d*, *d*¹ are rotatably supported between, and by, a pair of longitudinally extending beams 49 which are secured to the under side of the transverse beams 20, 21 of said table-sections. All of the wheels 48 on table-section *d* are disposed at one side of the longitudinal beams 22 and the wheels 48 for the sections *d*¹ are supported at the opposite side of said beams so that the wheels of one of said table-sections will be offset transversely relatively to the wheels of the other.

When one of the table-sections *d*, *d*¹ is to be lifted above track level for uncoupling a pair of wheels from a truck, the carriage *f* is moved lon-

itudinally of the pit and transversely of the drop table until rails 34^a are vertically aligned with the wheels 48 on the table-section to be shifted. The lifting-carriage is then raised to elevate the said table-section above track-level so that the wheels can be uncoupled. When the locking-mechanism for said section is released from section c and beams m in the pit-wall, said section can be dropped to lower the uncoupled pair of wheels into the pit for transfer to another track. Wheels 48 are provided with flanges for engaging the sides of rails 34^a to hold the wheels against transverse movement on the lifting-carriage during the raising and lowering of said wheels. When either end-section of the table has been loaded with a pair of wheels and transferred and lifted to another floor-track, it can be rolled across the pit on rails 34^a and onto the floor-rails at the opposite side of the pit or can be rolled onto the floor-rails at the adjacent side of the pit. Either of sections d , d^1 can be operated in the same manner.

Each table-section d , d^1 is also provided with mechanism for manually propelling it, with its load, on rails 34^a . This mechanism comprises a vertical shaft 50 which is slidably and rotatably mounted in a pair of brackets 51 secured to one of the side-beams 19 ; a crank 52 fixed to the upper end of shaft 50 ; a bevelled pinion 53 splined to shaft 50 and held against vertical movement; a bevelled gear 54 meshing with pinion 53 ; a cross-shaft 55 for gear 53 journaled in bearings 56 fixed to the transverse beams of said table-section; pinions 57 fixed to shaft 55 ; and gears 58 fixed to the wheels 48 and engaging pinions 57 . Crank 52 and shaft 50 are lowerable to move the crank out of the way when not in use. A spring-detent 59 is adapted to engage a groove 60 at the lower end of shaft 50 to hold crank 52 and said shaft raised during the operation of the crank to propel the table-section. This propelling mechanism facilitates the transfer of a single pair of wheels from the lifting-carriage to the desired place for repair. Flooring g is suitably supported on each of the table-sections between, and at the outer sides of, the rail-sections c^2 , c^4 , as well understood in the art.

The construction set forth exemplifies a table-top comprising a central section adapted to be supported from the pit-walls and end-sections which can be conjointly raised or lowered by the lifting-carriage by positioning the lifting-carriage centrally and transversely of the top and by shifting the lifting-carriage to one side of the center for raising and lowering one of the end-sections and shifting the lifting-carriage to the opposite side of said center for raising and lowering the other end table-section. It also exemplifies a compound table-top in which the end-sections are provided with wheels for transporting them across, and from, the lifting-carriage onto the floor-tracks which are stationarily mounted on the table-sections, the lifting-carriage being adapted to be positioned for selective engagement with the wheels of the sections, respectively.

The invention exemplifies a drop-pit apparatus in which a compound table-top composed of a central section is provided with beams adapted to bridge and to be supported from the pit-walls and end-sections conterminous with the longitudinal beams of the pit, all the sections being conjointly lowerable by the lifting-carriage and the end-sections being separately lowerable independently of the central section.

The invention also exemplifies a compound drop-apparatus in which the table comprises a plurality of sections, one of which is lowerable independently of the other and is provided with wheels and the lifting-carriage is provided with rails for the wheels which extend completely across the pit so that the wheel-section can be rolled directly from the lifting-carriage to the floor-tracks at either side of the pit.

10 The invention also exemplifies drop-pit apparatus in which the table comprises central and end-sections and either of the end-sections can be separately engaged by the lifting-carriage by lateral movement of the carriage in the pit for selectively dropping either of the end-sections.

15 The invention also exemplifies a drop-table which comprises an independently lowerable section which is provided with propelling mechanism for expediting the delivery of a pair of wheels to the place for repair.

20 The invention is not to be understood as restricted to the details set forth, since these may be modified within the scope of the appended claims, without departing from the spirit and scope of the invention.

25 Having thus described the invention, what I claim as new and desire to secure by Letters Patent is:

1. In drop pit apparatus, the combination with 30 a drop-table comprising a plurality of vertically movable table-sections, one of which is separable from, and lowerable independently of, the other, and provided with wheels, and means for releasably supporting the sections in pit-bridging position, of a lifting carriage movable vertically and laterally in the pit and provided with rails extending across the pit and adapted to engage the wheels for separately shifting the independently lowerable table-section, and means on both sections, laterally offset relatively to the wheels, and adapted to be engaged by the carriage-rails for conjointly shifting them.

2. In drop pit apparatus, the combination with 35 a drop-table comprising a central vertically movable section, and a pair of end-sections each of which is separable from, and lowerable independently of, the central section, each end-section provided with wheels relatively offset transversely of the table, and means for releasably supporting the sections in pit-bridging position, of a lifting-carriage movable vertically and laterally in the pit and provided with rails extending across the pit and adapted to engage the wheels and separately shift either of the independently lowerable table-sections, and means on the sections, laterally offset relatively to the wheels and adapted to be simultaneously engaged and shifted by the rails on the carriage solely by lateral and vertical movements of the carriage relatively to the sections.

3. In drop pit apparatus, the combination with 40 a drop-table comprising a plurality of sections, one of which is separable from, and lowerable independently of the other, and provided with wheels, means for releasably supporting the sections in pit-bridging position, of a lifting-carriage movable vertically and laterally in the pit and provided with rails extending to the ends of the carriage and entirely across the pit and adapted to engage the wheels for separately shifting the independently lowerable section and on which said latter section can be rolled off the carriage onto the floor at either side of the pit.

4. In drop pit apparatus, the combination with 45 a drop-table comprising a plurality of sections,

one of which is separable from, and lowerable independently of the other, and provided with fixed bearings and wheels mounted in said bearings, means for releasably supporting the sections in pit-bridging position, of a lifting-carriage movable vertically and laterally in the pit and provided with rails extending to the ends of the carriage and entirely across the pit and adapted to engage the wheels for separately shifting the independently lowerable section and on which said latter section can be rolled to either side of, and off, the carriage.

5. In drop-pit apparatus, the combination with a drop-table comprising a vertically movable central section and end-sections, and adapted to extend completely across a drop pit, the table-sections being provided with rail-sections to form a track across the pit, the end-sections being separable from, and lowerable independently of, the central section, means for releasably supporting the table-sections in pit-bridging position, the end-sections being provided with wheels, of a lifting-carriage movable vertically and laterally in the pit, provided with tracks which, by the lateral movement of the carriage relatively to the table are adapted to be positioned for, and by vertical movement of the carriage, to separately engage and shift the wheels on either of the end sections.

6. In drop pit apparatus, the combination with a drop-table comprising a vertically movable central section and end-sections and adapted to extend completely across a drop-pit, the table-sections being provided with rail-sections to form a track across the pit, the end-sections being separable from, and lowerable independently of, the central section, means for releasably supporting the table-sections in pit-bridging position, the end-sections being provided with wheels, the wheels on one end-section being offset laterally relatively to the wheels on the other, of a lifting-carriage movable vertically and laterally in the pit, and provided with tracks extending across the pit which, by the lateral movement of the carriage relatively to the table are adapted to be positioned for, and by vertical movement of the carriage, to separately engage and shift the wheels on either of the end sections.

7. In drop pit apparatus, the combination with a drop-table comprising a vertically movable central section and end-sections and adapted to extend completely across a drop pit, the table-sections being provided with rail-sections to form a track across the pit, the end-sections being separable from, and lowerable independently of, the central section, means for releasably supporting the table-sections in pit-bridging position, the end-sections being provided with wheels, of a lifting-carriage movable vertically and laterally in the pit, and provided with rails extending to the ends of the carriage and completely across the pit, the wheels on the end-sections being laterally offset and positioned for separate engagement and shift by the carriage rails by

the lateral and vertical movements of the carriage relatively to the table.

8. In drop pit apparatus, the combination with a drop-table comprising a vertically movable central section and end-sections, and adapted to extend completely across a drop pit, the table-sections being provided with rail-sections to form a track across the pit, the end-sections being separable from, and lowerable independently of,

10. the central section, means for releasably supporting the table-sections in pit-bridging position, the end-sections being provided with wheels, of a lifting-carriage movable vertically and laterally in the pit, and provided with rails extending to the ends of the carriage and completely across the pit and adapted to alternately engage the wheels on the end-sections by lateral and vertical movements of the carriage relatively to the table, and on which either of the end-sections can be rolled across the pit and onto the floor.

15. 9. In drop pit apparatus, the combination with a drop-table comprising a plurality of table-sections, one of which is separable from, and movable independently of, the other, the separably lowerable section being provided with wheels, of a lifting carriage movable vertically and laterally in the pit and provided with rails adapted to engage the wheels, and manually operable propelling mechanism mounted on the separably lowerable section for transporting said latter section on the rails of the lifting carriage.

20. 10. In drop pit apparatus, the combination with a drop-table comprising a plurality of table-sections, one of which is separable from, and movable independently of, the other, the separably lowerable section being provided with wheels, of a lifting-carriage movable vertically and laterally in the pit and provided with rails extending across the pit and adapted to engage the wheels, 40. and manually operable propelling mechanism on the separably lowerable section for transporting said latter section on the rails of the lifting-carriage, and comprising an operating element movable into position above the table and adapted 45. to be lowered when not in use.

11. In drop pit apparatus, the combination with a drop-table comprising a plurality of vertically movable table-sections, one of which is separable from, and lowerable independently of, the other, and provided with wheels mounted on shafts which are immovably fixed parallel to the plane of the table, and means for releasably supporting the sections in pit-bridging position, of 50. a lifting-carriage movable vertically and laterally in the pit and provided with rails extending across the pit and adapted to engage the wheels and 55. separately shift the independently-lowerable table-section, and means on both sections adapted to be engaged by the rails on the carriage for 60. conjointly lifting and lowering the sections, the wheels being adapted to run on the rails on the carriage when the wheeled section is separated from the other section.

HUGH K. CHRISTIE.
